PAPER MAKING MACHINE

Original Filed Aug. 15, 1921

3 Sheets-Sheet 3

The drawing illustrates a mechanical assembly, likely a conveyor or transport system, within a rectangular frame. Key components include:

- Fig. 3:** The main assembly features a central horizontal conveyor belt supported by a series of rollers (e.g., 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51).
- Fig. 4:** A detailed view of a wheel assembly, showing a hub (45) with a bearing (46) and a rim (47) with a hub cap (48). The assembly is mounted on a shaft (49) and includes a locknut (50) and a lock washer (51).

UNITED STATES PATENT OFFICE.

PAUL PRIEM, OF HEIDENHEIM-ON-THE-BRENZ, GERMANY, ASSIGNOR TO AMERICAN
VOITH CONTACT COMPANY, INC., OF NEW YORK, N. Y., A CORPORATION OF NEW
YORK.

PAPER-MAKING MACHINE.

Original application filed August 15, 1921, Serial No. 492,487, and in Germany November 21, 1919.

Divided and this application filed October 28, 1925, Serial No. 65,444.

Applications for patents have been filed in Germany November 21, 1919, No. 335,449, and April 29, 1920, No. 351,120, and in Great Britain filed March 15, 1921, No. 181,793.

5 The invention relates to paper making machines having an endless wire, and it has for its object to so construct the portion of the machine corresponding thereto that the wire can be rapidly exchanged. For this purpose, 10 arrangements are made for enabling the parts of the machine situated respectively above and below the wire to be moved relatively to each other in such a manner that the beams carrying the breast roller, the table 15 rollers and the suction boxes may be removed laterally out from the machine.

In the drawing several constructional forms of the invention are represented.

Fig. 1 is a side view of the endless wire section of a paper machine in which the carrying beams along with the register and suction devices may be lowered a certain distance until rollers mounted on the beams rest on rails, on which the beams with accessory portions may be moved out laterally.

Fig. 2 is a vertical cross section taken through the register part of Fig. 1.

Fig. 3 is a side view of an apparatus similar to that of Fig. 1 in which however, the 30 part above the wire may be elevated.

Fig. 4 shows the raising apparatus for the rear part of the carrying frame.

In the machine represented in Figs. 1 and 2 the wire parts of the machine commence 35 with the delivery chest 1 with the attached foam laths 2 which by means of the rod 3 is hung from the carrying frame 4 that is in turn mounted on the pillars 5 and 6. From this delivery chest the paper pulp passes in 40 a known manner to the endless wire 7. The latter is first carried by the table rollers 8 which are mounted in the shake rails 15, the rear extremities 16 of which are pivoted to the carrying beams 18 and are supported at 45 other points in their length and in a manner already known by the shake brackets 17. At the fore-end of the carrying beams 18 there is mounted the horizontally displaceable breast roller 9. At the end of the register 50 part the level roller 19 is arranged and following this are the suction boxes 20 beyond which at the far end of the bearing beam 18

the wire guide roller 36 is mounted. From this latter roller the wire 7 passes round the lower couch roller 10 on which rests the 55 upper couch roller 11 and is then conducted over the wire and tension rollers 12, 13, 14 and 15 back to the breast roller 9. On the wire 7 rest in a manner already known the deckle-straps 27 which run over the deckle 60 rollers 28 and 37 suspended from the rods 30 and 38 and which may, by means of the deckle carriage 26 which is hung from the frame 4 be displaced laterally.

The beams 18 are provided with rollers 21 65 resting on rails 22 that may be taken out. The latter rest on the hoist blocks 23 which may be raised or lowered by means of hand-wheels 25, and are provided, on the driving side of the machine with vertical arms 24 70 which serve as lateral fences for the guiding of the beams 18.

At right angles to the machine and forming a prolongation of the rails 22 there rest stationarily on the pedestals 32 the rails 31 (Fig. 75 2) which can be connected with the rails 22 by means of filling or bridge pieces 33, shown dotted in the figure, so that the rails 22 and 31 and the bridge pieces 33 may unite to form one continuous travelling way. When 80 it is intended to change the wire, first the inner wire rollers 13 and 15 are placed on hooks 62 provided on the under side of the beams 18, the wire is then cut through and rolled up in front of the couch rollers and 85 then taken out. Thereafter the hoist blocks 23 are by means of the hand wheels 25 so far lowered that the wire can completely clear the delivery chest 1 and the deckle straps 27, whereafter the beams 18 with the entire register and suction parts may be drawn out, on the rails 22, 33 and 31, towards the side 90 of the machine. When this has been effected, the rails 22 are removed from the machine and the new wire is drawn in. The wire is 95 subsequently with the aid of the two tension rollers 34 and 35 inserted at the fore end, brought into the position indicated in Fig. 1 by the line of dashes, whereupon the rails 22 are again put in the hoisting blocks 23 100 and the beams 18 with the register and suction devices are again inserted to the machine. The rollers 34 and 35 are then again taken out and the main wire rollers 12, 13,

14 and 15 instead brought to their working position, the new wire being now ready for use.

The relative separating motion of the upper and lower parts associated with the wire can also be effected by raising the upper part. The two motions can also be effected simultaneously so that the part situated above the wire may be raised, and the part below the wire may be lowered. An arrangement to accomplish this is shown in Fig. 3. The members bearing the register and suction devices are substantially the same as in the constructional form in Fig. 1, only here the hoisting blocks are arranged somewhat differently. In this case fixed standards 49 are provided which have, at their sides, guides for brackets 50, which may be elevated or lowered by means of the screw-shaft 51 and which carry the rails 22 whereon rest the rollers 21 of the beams 18.

The upper frame 4 is pivoted at its rear end by means of the bolts 44 to the pillars 6. At the fore end of the frame is mounted a worm shaft 40 which can be turned by means of the hand wheel 41, the worms of which engage with nuts 42 on the screw spindle 43 mounted on the upper ends of the pillars 5. By rotation of these nuts the fore end of the frame 4 can be so far elevated that the delivery chest 1 and the deckle straps 27 can clear the wire 7. If then further, the brackets 50 bearing the rails 22 be so far lowered by means of the screw spindles 51 that the register and suction devices which are carried by the beams 18, clear the wire then the beams 18, along with the register and suction devices may be pulled out laterally from the machine.

If it be desired also to raise the rear-end of the bearing frame 4, a similar apparatus may be arranged here as at the fore-end. In such a case, as may be seen in Fig. 4, a worm shaft 47 provided with a hand wheel 48 may be fitted at the rear-end of the frame 4, this shaft engaging nuts 46 of the screw spindles 45. In this way the carrying-frame may be

brought to a uniform elevation throughout its length.

The present application is a division of my copending application Ser. No. 492,487, filed August 15, 1921.

I claim as my invention—

1. A Fourdrinier machine having a table withdrawable laterally as an entity from within the wire loop, transversely extending rails arranged beneath the table at longitudinally spaced intervals, means for lifting and lowering the table with said rails, in combination with a second set of transversely extending rails arranged in register with the first set above mentioned, but to one side of the table, and spaced from said first set, removable bridge rail sections adapted to span the hiatus between the adjacent ends of the rails of each set, and roller means for effecting the lateral transfer of the table from the first to the second set of rails across the intervening bridge rail sections, to facilitate changing the wire.

2. A Fourdrinier machine having a table withdrawable laterally as an entity from within the wire loop, means for lowering the frame preliminary to its lateral withdrawal, a deckle strap frame arranged above the table, and means for lifting said frame to clear the strap from the wire, said lateral withdrawal of the table and lifting of the deckle strap serving to facilitate change of the usual wire screen.

3. A Fourdrinier machine having a table withdrawable laterally as an entity from within the wire loop, means for lowering the table preliminary to its lateral withdrawal, a deckle strap frame arranged above the table and pivoted at one end, and means for swinging the frame upward on its pivot, said lateral withdrawal of the table and upward swing of the deckle strap frame serving to facilitate change of the usual wire screen.

In testimony whereof I have signed my name to this specification.

PAUL PRIEM.
